(57) **CLAIM**

The ornamental design for a rear surface of a display panel, as shown and described.

DESCRIPTION

FIG. 1 is a rear view of a first embodiment of a rear surface of a display panel or portion thereof showing our new design;

FIG. 2 is a rear perspective view of a second embodiment of a rear surface of a display panel or portion thereof showing our new design; and,

FIG. 3 is a rear view thereof.

The dashed broken lines in the Figures are for the purpose of illustrating unclaimed portions of the a rear surface of a display panel and form no part of the claimed design. The dot-dash broken lines represent boundaries of the claimed design and do not form part of the claimed design. The shade lines in the Figures show contour and not surface ornamentation.

1 Claim, 3 Drawing Sheets
